APPARATUS FOR CLEANING GAS SWEPT
HEATING SURFACES

Bror Olof Broman, Stora Essingen, Sweden, assignor to Aktiebolaget A. Ekstroms Maskinaffar, Stockholm, Sweden

Application June 22, 1949, Serial No. 100,645

Claims priority, application Sweden
January 19, 1949

11 Claims. (Cl. 257—1)

1

This invention relates to a method and an apparatus for cleaning, during operation, heating surfaces swept by air or gas by using sand, fine gravel, granulated metal particles (particularly steel shot) or similar solid particles which are caused to drop by gravity on the heating surfaces, their falling speed in some cases being increased on account of the velocity of the gas along the surfaces, the particles, however, never being directly blown against the heating surfaces by the action of compressed air or the like.

Tests have established that in order to obtain the highest practical effect, the cleaning operation in accordance with this invention must be continuous. For this purpose a fixed portion of solid particles (for example steel pellets) which may be relatively small, is, by means of suitable arrangements, caused to circulate through the apparatus to be cleaned. The steel pellets or particles may also be cleaned during the circulation, possibly by washing, be dried and even cooled in order to save the transport devices.

For cleaning gas-swept heating surfaces for instance in boilers and economizers during operation blowing with steam or air is widely used.

In certain cases, especially for economizers and air pre-heaters heated with combustion gases from soda furnaces in cellulose plants the heating surfaces are cleaned during operation by means of water or some alkaline solution sprinkled or flushed thereon.

The above-mentioned cleaning methods suffer from serious disadvantages.

When blowing with steam or air, the cost of the requisite apparatus is relatively high, and the costs for steam and compressed air are also quite considerable.

The sprinkling with water or some alkaline solution entails risks to the heating surfaces on account of the resulting considerable temperature stresses which in many cases cause considerable damage to the constructions in a relatively short time.

When cleaning is effected by means of water, air or steam, it is necessary as a minimum to effect a cleaning operation once every eighth hour i. e. three times during each period of 24 hours in continuous operation of the plant.

It has further been suggested to employ sand-blasting, i. e. injecting solid particles with the aid of compressed air. However, in practice this method has not proved acceptable as the heating surfaces become damaged by the sandblasting.

The general object of this invention is therefore to provide a method of cleaning gas-swept

2

heating surfaces of a heat plant during operation at low costs and without any risks of damaging the heating surfaces or any other parts of the plant by using solid cleaning particles which are circulated through the plant and are caused to drop against the surfaces to be cleaned.

A further object of the invention is to provide apparatus by which the cleaning particles are circulated through the plant and caused to fall against the surfaces to be cleaned.

A still further object of the invention is to provide distributing means for spreading the cleaning particles over the surfaces to be cleaned in a predetermined manner prior to their falling against the surfaces to be cleaned.

Other objects and advantages of the invention will be disclosed in the following specification with reference to the attached drawings in which Fig. 1 shows an embodiment of the invention. Fig. 2 shows another embodiment and Fig. 3 shows a detail from Fig. 2 as viewed from another side. Figs. 4 and 5 show a side elevation and plan view, respectively, of a distributor for the steel pellets and Figs. 6 and 7 show corresponding views of another embodiment of such distributor.

As regards the drawing, Figure 1 discloses the invention with reference to heat interchanging apparatus that are associated with the boiler plant. The apparatus includes a casing 1 embodying side walls and a top wall. An upper gas inlet 1' communicates with the casing through a side wall thereof at an area adjacent the top wall and a lower gas outlet 1" communicates with the casing adjacent the lower extremity thereof. Within the casing are arranged tube means through which fluid passes for heat exchanging relationship with the gas that flows through the casing. The tube means include a preheater 2 for preheating primary combustion air, an economizer 3 consisting of spaced banks of tubes extending through the casing in a horizontal relationship and a preheater 4 for secondary combustion air. These respective tube means are mounted vertically above one another.

Above the casing is a container 5. This container at its lower end communicates through bifurcated ducts 5' with the two casings that are disclosed in the drawings. These ducts 5' each discharge into a funnel-shaped member 6, the lower end of which is extended by a hollow shaft which is rotatably mounted and projects through the top wall of the casing and terminates above the tube means therein that constitute the preheater 4. A rotary distributing member indicated generally at 7 is secured to the bottom

end of the hollow shaft and, as apparent from Figures 4 to 6, this rotary distributing member has an outer contour of spiral form that extends from the vicinity of the center rotation thereof outward toward and terminates at its greatest radius. An electric motor 8 and suitable gear means rotates the hollow shaft that supports the rotary distributing member 7 so that solid cleaning particles, for instance shot pellets, are effectively distributed within the casing above the tubes and spread throughout substantially the cross-sectional area of the casing so that they fall by gravity and cascade through the casing to impact and ricochet against the surfaces of the tubes to pick up material accumulated thereon and to dislodge material therefrom so as to clean the tubes. Beneath the casing and thus beneath the gas outlet are means for collecting the cleaning particles which includes a conduit 9 constituted by a return pipe connected to the container 5 at one end and its other end is in communication with a fan 10 that blows air through the conduit or pipe 9 for returning the particles to the container 5 so that continuous circulation can be maintained.

In the embodiment according to Fig. 2 a screw conveyor 11 and a bucket carrier 12 are substituted for the return pipe, but otherwise the apparatus is analogous to and operates in the same manner as the one according to Fig. 1. In the apparatus according to Fig. 3, the path of the gas from a boiler 13 through the apparatus is indicated by arrows, and the velocity of the flowing gas will contribute to the acceleration of the speed of the cleaning particles.

Figs. 4 and 5 show an embodiment of a distributor member. The numeral 14 designates the hollow shaft for feeding the cleaning particles, to which a plate 7 is secured, the contour of which follows a spiral line, said plate being provided with radial ridges 15. The purpose of this device is to bring about an even distribution of the cleaning particles over the cross section of the apparatus located underneath. On the plate, directly under shaft 14 a wear resistant plate 16 is arranged, having sloping sides in order to prevent the cleaning particles from collecting in a heap below the shaft; instead it is immediately shoved out to the periphery of the plate. The plate 16 is made of particularly wear-resistant material to insure long life of the distributor member. The plate forming the base of distributing member 7 extends transverse to the axis of the shaft 14 and is in spaced relation with respect to the lower end of this shaft. The vanes 15 that extend radially of the hollow shaft from the shaft toward and terminate at the outer marginal edges of the plate are substantially equi-spaced and of unequal length as shown in Figure 5.

Another distributing member for the same purpose is shown in Figs. 6 and 7 and consists mainly of two more or less conically shaped plates 17 and 18, arranged above each other and held together by radial walls and stays. The plates have a spiral-like, outside contour and the upper plate 17 is provided with an inlet 19, eccentrically fastened to the pipe 14. The eccentricity being adjustable, the desired distribution characteristics of the steel particles is attained in operation. Right below the inlet 19 is disposed a plate 20, having sloping sides and made of wear-resistant material to minimize the effect of wear and tear caused by the particles.

In the arrangement of Figures 6 and 7, the dis-

tributing member, as indicated, includes a collar constituting the inlet 19 and the conically shaped plates 17 and 18 each have the aforescribed spiral contour and the plate 18 is smaller than the plate 17. Radial vanes 15' arranged similarly to the vanes 15 of Figures 4 and 5 extend between the plates from the outer edges thereof toward and terminate adjacent the collar. The uppermost plate has an aperture therein at its apex and the insert 20 of wear resistant material is mounted in an aperture in the lowermost plate that is in alignment with the aperture in the uppermost plate.

In order to limit the free fall of the particles, groups of spaced rods 1' extend between the walls of the casing above the tubes to be cleaned but in spaced relation beneath the distributing member.

It is therefore clear that the solid cleaning particles are continuously fed to the distributing member and effectively distributed throughout the entire cross-sectional area of the casing so that they fall downwardly therethrough in the same direction as the gas flow striking the outer surface of horizontally arranged tubes and passing between the tubes of nests of tubes and thus internally of the vertically arranged tubes of the preheater 2.

The cleaning particles may be introduced by means of a low-speed air blow or blast, but no real sand-blowing effect may be directed towards the heating surfaces proper.

The method according to the present invention has proved most valuable especially when the gases carry a large percentage of solid matter, or when said matter is of a sticky nature, causing injurious coatings on the heat surfaces, or when the gases contain substances which chemically attack these surfaces. Besides, the apparatus according to this invention is less expensive, both as to cost and operation, than the methods and apparatus heretofore used for the purpose.

From practical tests according to the invention, when using steel pellets, it has been established that the height of free drop of the solid particles should preferably not be too long. For this purpose, for instance, one or more sets of rods may be arranged, preferably above the topmost set of tubes in the boiler, to prevent the pellets from falling directly on the tubes. For different tubes, the height of free fall for the particles of pellets has different maximum values. In some cases it should not be more than 250 mm. above the topmost group of tubes to break the fall. The size, shape and weight of the particles also have influence upon the cleaning effect, imparted to the heating surfaces.

Having now described my invention, what I claim as new and desire to secure by Letters Patent is:

1. In heat interchanging apparatus, a casing including side walls and a top wall, an upper gas inlet communicating with the casing through a side wall thereof adjacent the top wall and a lower gas outlet communicating with a side wall of the casing, tube means within said casing and through which fluid passes for heat exchanging relationship with gas flowing through the casing, a rotatable hollow shaft projecting through the top of the casing and terminating above the tube means therewithin, a rotary distributing member secured to said hollow shaft and said member having an outer contour of spiral form extending from the vicinity of the center of rotation thereof outward toward and terminating at its great-

75

est radius, means for feeding solid cleaning particles into the hollow shaft so that said particles are distributed within the casing above the tubes and spread throughout substantially the cross-sectional area of the casing to fall by gravity and cascade through the casing and impact and ricochet against the surfaces of the tubes to pick up material accumulated thereon and to dislodge material therefrom to clean the tubes, and means beneath the casing and beneath the gas outlet to collect said cleaning particles after they have passed through the casing.

2. In heat interchanging apparatus as defined in and by claim 1, in which said rotary distributing member is eccentrically and adjustably secured to said hollow shaft.

3. In heat interchanging apparatus as defined in and by claim 1, in which said rotary distributing member is fixedly secured to said hollow shaft comprises a plate extending transversely of the axis of the shaft and in spaced relation with respect to the terminal end of the shaft, said plate having the said outer contour of spiral form extending from the vicinity of the center of rotation of the shaft outward toward and terminating at its greatest radius, and vanes mounted on said plate and extending radially of said hollow shaft from the shaft to and terminating at the outer marginal edge of the plate, said vanes being substantially equi-spaced and of unequal length.

4. In heat interchanging apparatus as defined in and by claim 3, in which said plate is of wear resistant material to minimize wear occasioned by the movement of the cleaning particles relative to the plate.

5. In heat interchanging apparatus as defined in and by claim 1, in which said rotary distributing member includes a collar, vertically spaced plate members carried by the collar and having said spiral outer contour, said plate members further having conical shape in cross-section and the lowermost plate being smaller than the uppermost plate, radial vanes extending between the plates from the outer edges thereof toward and terminating adjacent the collar, said uppermost plate having an aperture therein at the apex thereof surrounding said collar.

6. In heat interchanging apparatus as defined in and by claim 5, in which the lowermost plate has an aperture therein at the apex thereof and an insert of wear resistant material disposed in said aperture to minimize wear occasioned by movement of said particles relative to said plate.

7. In heat interchanging apparatus as defined in and by claim 1, and further including particle receiving means disposed above said casing and conveying means extending between the collecting means and said particle receiving means to convey particles from the collecting means to the

receiving means and conduit means connecting said receiving means with the said feeding means.

8. In heat interchanging apparatus as defined in and by claim 1, and groups of spaced rods supported within the walls above the tubes and spacedly beneath said distributing member to limit the height of free fall of the cleaning particles.

9. Means for cleaning gas-swept heating surfaces of heat interchanging apparatus, which apparatus is of the type embodying walls defining a casing and means providing heat exchange surfaces within the casing and gas inlet and outlet means communicating with the casing, comprising a rotary distributing member disposable within the casing directly above the surfaces to be cleaned, said member having an outer contour of spiral form extending from the vicinity of the center of rotation thereof outward toward and terminating at its greatest radius, and means for feeding solid cleaning particles to said distributing member so that the particles are simultaneously introduced within and spread throughout substantially the cross-sectional area of the casing directly above the surfaces to be cleaned.

10. A rotary distributing means for simultaneously introducing and distributing solid cleaning particles within the walls of a casing of a heat interchanging apparatus and above the heat exchange surfaces within the casing that are to be cleaned, comprising a hollow rotatable shaft and means providing rotary distributing surfaces extending transversely of the axis of the shaft and having an outer contour of spiral form extending from the vicinity of the center of rotation of the shaft outward toward and terminating at the greatest radius of said member, spaced radial vanes extending inwardly from the outer edge of said transversely extending means toward said shaft, and means securing said transversely extending means to said hollow shaft.

11. A rotary distributing means as defined in and by claim 10, in which said last mentioned means adjustably eccentrically secure said transversely extending means to said hollow shaft.
